UNITED STATES PATENT OFFICE

112,223

DESIGN FOR WRAPPING PAPER OR SIMILAR ARTICLE

Ludolph P. Welanetz, North Plainfield, N. J., assignor to Koh-I-Noor Pencil Factory L. & C. Hardtmuth, Inc., Bloomsbury, N. J., a corporation of New Jersey

Application April 26, 1938, Serial No. 76,755

Term of patent 14 years

To all whom it may concern:

Be it known that I, Ludolph P. Welanetz, a citizen of the United States of America, residing at North Plainfield, in the county of Somerset and State of New Jersey, have invented a new, original, and ornamental Design for Wrapping Paper or Similar Article, of which the following is a specification, reference being had to the accompanying drawing, forming a part thereof.

The figure is a plan view of wrapping paper or similar article, showing my new design.

I claim:

The ornamental design for wrapping paper or similar article, as shown.

LUDOLPH P. WELANETZ.
